CLAIM

The ornamental design for an automated library terminal for dispensing and accepting return of reusable articles, as shown and described.

DESCRIPTION

FIG. 1 is a front elevational view of an automated library terminal for dispensing and accepting return of reusable articles showing my new design;

FIG. 2 is a side elevational view thereof, the opposite side being a mirror image;

FIG. 3 is a top plan view thereof;

FIG. 4 is a front, side perspective view thereof;

The rear and bottom views are flat and unornamented.

FIG. I

FIG. 2

FIG. 3

FIG. 4
